BURNER CONTROL APPARATUS

Charles V. Hildebrrecht, Chicago, Ill., assignor to
 Milwaukee Gas Specialty Company, Milwaukee,
 Wis., a corporation of Wisconsin

Application February 11, 1942, Serial No. 430,378

10 Claims. (Cl. 236—1)

This invention relates, generally, to apparatus for controlling fluid flow in conduits, and it has particular relation to improvements in burner control apparatus of the character employing an electromagnet which is effective, when energized, to maintain a valve or other controlling member in open or operating position but which is ineffective to move the valve or other controlling member from closed or safety position to open or operating position.

An illustrative example of such a burner control apparatus is apparatus in which there is an electrical operating circuit for the electromagnet and a thermoelectric generator energized by the heat of a pilot light or other flame for supplying current to the operating circuit.

The present invention may be embodied in a wide variety of constructions for use with a wide variety of devices employing gas or other fuel burners. For purposes of illustration I shall refer to a number of illustrative devices with which the present invention is adapted to be used, but it is to be understood that the invention is not necessarily limited to use with the particular devices herein set forth.

Due to the minute character of the maximum electromotive force that can be generated by the heat of a pilot light or other flame or source of heat on a thermoelectric generator and the inability of this minute electromotive force to actuate the main shutoff valve or controlling member from closed or safety position to open or operating position, thermoelectric control and safety shutoff devices heretofore have usually required manual cocking or reset means, such as a cocking or reset button, for cocking or resetting the device after each operation to closed or safety position.

As a result, these thermoelectric control and safety shutoff devices usually have not been automatic or completely self-operating. For example, if a thermostat or other condition-responsive control were employed for opening or disabling the thermoelectric circuit for operation of the valve to closed position at one predetermined temperature or other condition, and for closing or rendering the thermoelectric circuit operative at another temperature or condition, the closing or rendering operative of the thermoelectric circuit—with the pilot light or other flame burning and heating the thermoelectric generator—would not open the valve because the minute electromotive force would not accomplish that result.

Consequently, with the usual thermoelectric

control devices heretofore provided, it has been necessary to reset the shutoff valve to open position after the failure of the pilot light or other flame, and if a thermostat or other condition-responsive control were employed with such a device it would be necessary to reset the shut off valve to open position after each closing of such valve under the action of the thermostat or other condition-responsive means.

10 In that pilot failure usually occurs only infrequently, the matter of resetting the device after the failure of the pilot light is not objectionable, but any necessity for resetting the device after each operation of the valve or other controlling member to closed or safety position under the action of the thermostat or other condition-responsive means presents a difficult practical problem.

I am aware of the prior art provisions for eliminating the necessity of manual cocking or reset means, and the necessity of a manual cocking or resetting operation. In these prior art devices however, the main shutoff valve or other controlling member is not only held in open or operating position by the minute thermoelectromotive force, but is actually moved from closed or safety position to open or operating position through the instrumentality of this minute thermoelectromotive force, which is quite different from the theory of the present invention.

One of the main objects of the present invention is to provide a device having means which is held in position for holding the shutoff valve or controlling member in open or operating position as long as the electromagnet is energized, for example, by the heat of the pilot light or other flame on the thermoelectric generator and, in conjunction therewith, means for automatically operating the shutoff valve or controlling member to closed or safety position, and, if desired, to open or operating position under the action of a thermostat or other condition-responsive control and without releasing the first mentioned means from the position in which it is held by the electromagnet.

Another and more specific object of the invention is to provide in a control system of the class described wherein there is a fluid supply conduit, a valve for controlling the supply of fluid through the conduit, a movable armature operable to control the valve, an electromagnet for the armature, a thermoelectric generator connected in circuit with the electromagnet for energizing the electromagnet to hold the armature in attracted position, and reset means for resetting the arma-

ture to attracted position, the combination with such system of condition responsive means and particularly a thermostat operable to close the valve and, if desired, to open the same while the armature remains held in attracted position by the electromagnet.

One of the advantages of the features set forth is the ability with a thermoelectric safety device to secure automatic "on" and "off" thermostat or other condition responsive control without requiring a resetting operation after each "off" operation of the thermostat or other condition responsive means and without requiring actual movement of the main shutoff valve to open or operating position through the instrumentality of the minute thermoelectromotive force.

While the particular structural features by which I obtain a device of the character set forth are important features within the more specific aspects of the invention, it is to be understood that the precise features shown and described may be varied within the broader aspects of the invention.

In order to acquaint those skilled in the art with the manner of constructing and operating a device in accordance with the present invention, I will now describe, in connection with the accompanying drawings, one illustrative embodiment of the invention.

In the drawings:

Figure 1 is a front view of a safety switch embodying the present invention, partially in section and with the cover removed and showing the switch in closed position;

Figure 2 is a detail section taken on the line 2—2 of Figure 1;

Figure 3 is a detail section taken on the line 3—3 of Figure 2;

Figure 4 is a more or less diagrammatic view showing the switch in side elevation and in connection with burner apparatus;

Figure 5 is a fragmentary detail view showing the position of the switch actuator and reset means, with the reset member pressed inwardly to cock or reset the device; and

Figure 6 is a view similar to Figure 5 showing the position of the switch actuator and reset means with the switch in open position and the reset member and reset stem released.

In Figure 4 of the drawings, a gas or other fuel burner of any suitable or preferred type is conventionally illustrated at 10. The burner 10 may be the burner of a room or space heater, water heater, floor furnace, gas range, or any other burner. A gas or other fuel supply pipe 11 leads to the burner 10 for the delivery of gas or other fuel thereto—for example, through a mixing chamber (not shown) to which air is admitted in the usual way as well understood in the art.

A power actuated or electroresponsive valve 12, such as a solenoid or motor valve, is interposed in the fuel supply pipe 11. The valve 12 shown as comprising a valve body 13 and a hood 14 having suitable power operated valve actuating means therein. A step-down transformer 15 supplies power for the operation of the valve 12. This transformer comprises a line voltage primary 16 and a low voltage secondary 17. The primary 16 is connected to line wires 18 leading to any suitable source of current or power (not shown). The valve actuating means for the valve 12 is connected into the secondary circuit 19. The safety switch and thermostat or other condition responsive control is also connected into the secondary circuit 19 as will presently appear.

For purposes of illustration it may be assumed that the valve 12 is of a character to be actuated to open position by closing of the circuit 19 and to be held in open position to supply fuel or operative energy to the burner 10 as long as the circuit 19 is closed. The valve 12 may have spring means, or other suitable means, for actuating the valve to closed position to shut off the supply of fuel to the burner 10 when the circuit 19 is opened or otherwise disabled.

The safety switch per se selected for illustration is similar to that more fully disclosed in the copending application of Harold A. Mantz, Serial No. 394,601, filed May 22, 1941, but it is to be understood that the construction and operation of the safety switch part of the combined safety and thermostat or other condition responsive control of the present invention may, within the broader aspects of the invention, be of any other suitable or preferred form.

The safety switch and thermostat control is shown as located within a housing 20. The opposite ends of the back wall of the housing are turned in to form end walls 21, and, at the opposite sides of the back wall, are inturned flanges 22. The cover 23, which may be of generally U-shaped cross section, fits over the inturned end walls 21 with the inner marginal edges of the sides of the cover fitting over the flanges 22.

Slots 24, opening inwardly from the inner marginal edges of the side walls of the cover fit over the shanks of screws 25 which have threaded engagement in the side flanges 22. The screws 25 are adapted to be tightened to secure the cover in place on the base of the housing, and to be loosened to permit removal of the cover. The screws 25 and slots 24 may be positioned at different distances from the opposite ends of the device to assure proper mounting of the cover 23.

The front wall of the cover 23 has an opening 26, shown in dotted lines in Figure 4, through which an indicator is adapted to be viewed to indicate the position of the switch as will herein-after appear.

An actuator or reset member 30 operates between open and closed positions by rectilinear movement through an opening 31 in the adjacent end wall 21 of the housing. The outer end of the actuator member 30 is provided with an operating button 32. The actuator member 30 is shown as comprising a pair of actuator member parts forming a fork at the inner end of the actuator member and secured together outwardly of the forked inner end. A pin 34, secured in the actuator member 30 outwardly of its forked inner end, cooperates with the adjacent end wall 21 to limit outward movement of the actuator member.

The actuator member 30 is yieldingly retained in its outwardly projected position as shown in Figures 1 and 6 and upon release of the button 32, as will presently appear, is returned to this outwardly projected position by a coiled return spring 36. This spring 36 is shown as connected between the inner end of the actuator member 30, at 37, and a spring anchoring lug 38 pressed inwardly from the adjacent end wall 21 of the housing.

A reset member 40 extends between the sides of the forked inner end of the actuator member 30. The inner end of the member 40 has a bifurcation or slot at 41 within which a cam lever 42 is pivoted on a pin 43, the opposite ends of which pin extend into longitudinal slots 44 in the opposite sides of the forked inner end of the actuator member 30. The cam lever 42 has a cam slot

45 through which extends a pin 46, the opposite ends of which are secured in the opposite sides of the forked inner end of the actuator member 30.

The cam lever 42 has secured thereto, for example, at 48, an overtravel spring arm 49 for actuating the switch to closed position. The lever 42 also carries a flag or indicator member 50. This indicator member 50 has "on" and "off" markings thereon as shown, or is provided with colored or other appropriately marked portions for indicating through the opening 26 in the switch cover 23 the position of the switch, as will presently appear.

The means for holding the reset member 40 in the position shown in Figure 1, so that the switch will close when the actuator member 30 is released following its inward resetting movement, and will remain closed as long as the member 40 is held in the position shown and the actuator member 30 is in its outwardly projected position, is shown in the form of an electromagnet located within the housing 20. The electromagnet selected for illustration comprises a magnet frame 56 secured, for example, to a terminal bushing 57 in the manner more fully disclosed in the co-pending application of Clarence Wantz, Serial No. 328,923, filed April 10, 1940. The coil of the electromagnet is wound around the legs of the magnet frame 56. The bushing 57 is shown as extending through an opening 59 in the adjacent end wall 21 and is externally threaded for threaded engagement at 60 with a nut 62 by means of which the bushing is clamped in place in the end wall 21 of the switch housing.

The electromagnet has an armature 64 attached at 65 to the adjacent end of a stem 66, if desired, in a manner to permit self-accommodation of the armature, when in attracted position, to the pole ends of the magnet frame 56. The electromagnet and armature are enclosed within a cup 68. The stem 66 extends for reciprocatory movement through an opening 69 in the inner end of the cup 68. The opening 69 is sealed by suitable sealing material such as a leather washer, felt packing or the like, as indicated at 70, interposed between the inner end of the cup 68 and a spring seating disc 72. The end of the stem 66 opposite the end on which the armature 64 is mounted is secured, for example, by a pin 73 to the adjacent end of the reset member 40. A coiled spring 74, interposed between the spring seating disc 72 and a spring seat member 75, actuates the armature 64 to retracted position and the reset stem 66 and reset member 40 to the position shown in Figure 6 when the electromagnet is deenergized, for example, upon extinguishment of the flame to which the device is responsive.

The particular switch selected for illustration is indicated in its entirety at 78 and is shown as comprising a pair of contacts or contact pins 80 positioned in spaced relation and suitably insulated from each other and the other parts of the device. The contact pins 80 are connected to terminals 82. The conductors 19 of the circuit for the valve 12, which conductors are insulated at 84, enter the housing 20 through an insulating grommet 85. One of the conductors 19 is connected to the terminal 82 for one switch pin 80, and the other conductor 19 is connected to the other terminal 82 for the other switch pin 80.

The switch stem 88 has rectilinear sliding movement in the insulating base or block of the switch 78, with the outer end of the stem in position for cooperation with the switch operating

5 spring arm 49 on the cam lever 42. Within the switch block the reduced inner end of the stem 88 passes through a bridging contact plate 90. A coiled spring 92 surrounding the reduced inner end of the stem 88 and interposed between the contact plate 90 and an abutment 93 on, or forming a part of, the switch base yieldingly urges the plate 90 out of bridging contact with the contacts 80 to open the circuit 19. By engagement of the contact plate 90 with the shoulder 94 on the stem 88, the spring 92 also yieldingly urges the stem 88 to its outwardly projected position as shown in Figure 6. Stop means (not shown) may be provided for limiting the outward movement of the switch pin 88 under the action of the spring 92.

10 The pilot burner 95, which is located in juxtaposition to the main burner 10 to maintain a pilot light for lighting the main burner, is supplied with gaseous fuel by a pilot supply pipe 96. The pilot supply pipe 96 may be connected with the main fuel supply pipe 11 anterior of the valve 12, or it may be supplied with fuel for delivery to the pilot burner in any other desired manner.

15 A thermoelectric generator, in the form of a thermocouple indicated at 98, is placed in position so that the hot junction 99 thereof will be heated by the pilot flame as long as the pilot flame is burning. The construction of the thermocouple 98 may be similar to that more fully disclosed in Oscar J. Leins Patent No. 2,126,564, granted August 9, 1938, or a thermopile or any other form of thermoelectric generator may be employed.

20 For the purpose of the present description suffice it to state that the particular thermocouple 98 selected for illustration comprises an outer tubular thermocouple member and an inner metallic thermocouple member of different thermoelectric characteristics. The inner thermocouple member is joined at one end to the outer end of the outer thermocouple member to form the thermojunction 99 which is placed in position to be heated by the pilot flame. An inner lead conductor 100 is joined to the inner thermocouple member to form an internal thermojunction 102, and an outer tubular lead conductor 103 is connected to the outer thermocouple member, for instance through a sleeve, to form a third thermojunction. The lead conductors are preferably of flexible character so as to be readily bent to insure neat installations. The inner lead conductor 100 is insulated from the outer lead conductor 103, for instance, by a wrapping of insulation 104 on the inner lead conductor.

25 A quick detachable or removable connection is preferably provided between the coil 58 of the electromagnet and the ends of the leads 100 and 103 opposite the ends which are connected to the thermocouple. This removable lead connection may be of the form disclosed in the co-pending application of Clarence Wantz hereinbefore identified and as illustrated in that form, although it may be of any other suitable or preferred form. Suffice it to state that the inner lead 100 has a connector cone 105 which seats in the correspondingly recessed outer end of the terminal tip 106 and is clamped in contact therewith by a connector sleeve 107. The adjacent end of the outer tubular lead conductor 103 is connected in circuit with one side of the coil 58 through the bushing 57, and the other side of the coil is connected to the terminal tip 106, the parts being suitably insulated as shown.

30 To start the operation of the system shown in

the drawings, as thus far described, the following sequence is followed:

The actuator or reset member 30 is pressed inwardly from the position shown in Figure 6 by engaging the button 32 with the hand or fingers and imparting pressure thereto. The armature 64 is in released or retracted position, and the spring 74 holds the pin 43 in engagement with the inner ends of the slots 44. As a result, the inward movement of the actuator member 30 moves the reset stem 66 with it in the same direction until the armature 64 is cocked or set into attracted position against the pole ends of the magnet frame 56.

The pilot burner 95 is lighted, or, having been lighted, heats the thermoelectric generator, and the actuator member 30 is held pressed inwardly until the heat of the pilot flame on the thermoelectric generator has energized the electromagnet sufficiently so that it will hold the armature 64 attracted thereto.

When the electromagnet is energized sufficiently to hold the armature 64 in attracted position, the actuator member 30 is released and the reset stem 66 and reset member 40 remain in cocked position, holding the pivot 43 for the cam lever 42 in the position shown in Figure 5. The switch operating spring arm 49 assumes the position shown in Figure 5 when the actuator member 30 is pressed inwardly. Then, with the armature 64 held attracted to the magnet frame 56, thereby holding the pivot 43 for the cam lever 42 in the position shown in Figure 5, when the actuator member 30 is released the outward movement of the actuator member 30, under the action of the spring 38, causes the pin 46, by its outward movement in the cam slot 45, to swing the arm 48 in a counterclockwise direction (Figures 1 and 5) about the pivot 43 from the position shown in Figure 5 to the position shown in Figure 1. The arm 48, by cooperation with the outer end of the switch pin 88 in this movement, moves the contact plate 90 inwardly against the action of the spring 92 and into bridging contact with the contacts 80 to close the circuit 19. The circuit is thus closed not by the inward movement of the actuator member 30, but by the movement of this member 30 to its outwardly projected position following the resetting operation and only when the electromagnet is effective to hold the armature 64 in attracted position. The overtravel character of the spring arm 48 assures good firm contact of the contact plate 90 with the contacts, there being preferably some overtravel of the cam lever 42 after engagement of the contact plate 90 with the contacts 80 which tensions the spring arm 48 to assure firm and tensioned contact.

If the pilot burner is not lighted to produce the thermoelectric current for holding the armature 64 in attracted position upon setting the same to that position by the actuator member 30, the armature 64 and reset stem 66 will move to retracted position upon release of the actuator member 30, the spring 92 at this time maintaining the switch plate 90 in open position.

If, after the parts are set as shown in Figure 1 and the pilot burner is lighted to hold the parts in the position shown in this figure, the pilot burner is extinguished, the armature 64 is released and the spring 74 then operates to move the armature to retracted position. The cam lever 42 moves outwardly with the movement of the reset stem 66 to released position through the pin connection at 43, and the cam slot 45, 75

cooperating with the pin 46 by this movement of the cam lever 42 relative to the actuator member 30, swings the arm 48 in a clockwise direction about the pivot 43 to the position shown in Figure 6. This releases the switch pin 88, and the spring 92 separates the contact plate 90 from the contacts 80. This opens or interrupts the circuit 19, and the valve 12 operates to closed position to shut off the supply of fuel to the main burner.

When the armature is in retracted position with the actuator member 30 in released position as shown in Figure 6, the "off" marking on the indicator arm is positioned to be viewed through the opening 26 in the cover of the housing to indicate that the switch is "off." When the armature is in attracted position and the actuator member 30 is in its outwardly projected position as shown in Figure 1, the "on" marking on the indicator arm 50 is positioned to be viewed through the opening 26 to indicate that the switch is "on" or closed.

The thermostat control is shown for purposes of illustration as comprising a bimetallic element of helical form. It is to be understood that any other suitable or preferred form of thermostat may be employed, and that, if necessary or desired, the device may be modified for use with other forms of thermostats—for example, of the bimetallic arm type, bimetallic coil type, bellows type, or any other type for use with room or space heaters, or for use with hot water heaters, or as a limit control or otherwise as desired.

It is to be further understood that within at least certain aspects of the invention, condition responsive controls other than thermostat controls may be used in place of the thermostat control.

The bimetallic element 125, as shown for purposes of illustration, surrounds a shaft 126 journaled for turning movement, for example, in the back wall of the housing 20. One end of the bimetallic element 125 is secured at 128 to the outer end of the shaft 126. The other end of the bimetallic element may be secured to an adjusting lever 130 which is mounted to be turned about the axis of the shaft 126 and relative to the shaft. The adjusting lever 130 has a pointer 132 which cooperates with the temperature markings on the dial 134.

The end of the shaft 126 opposite the end which is secured to the bimetallic element 125 extends into the housing 20 and carries, for turning movement therewith, a tripping lever 135. The tripping lever 135 cooperates with the extended free outer end of the spring arm 48, or otherwise with this arm as suitable or desired.

When the selected temperature is reached as determined by the setting of the pointer 132 along the temperature markings on the dial 134, the bimetallic element 125 turns the shaft 126, and thereby the arm 135, in a counterclockwise direction from the position shown in Figure 1. Assuming that the armature 64 is held in attracted position by the energization of the electromagnet by the heat of the flame on the thermoelectric generator and that the actuator member 30 is in released position and the switch closed as shown in Figure 1, this counterclockwise movement of the tripping lever 135 forces the spring arm 48 outwardly away from the switch operating member or pin 88. The spring arm 135 is moved, for example, to the position indicated generally in dotted lines in Figure 1, and as a result, the

switch opens under the action of the spring 92 with a resulting closing of the valve 12 to shut off the supply of fuel to the main burner.

It is to be noted that the closing of the valve 12 under the action of the thermostat is effected through at least a part of the mechanism through which the valve is maintained open by the attraction of the armature 64 to the electromagnet. And what is particularly important is the fact that this thermostat closing of the valve is accomplished without releasing the armature from the electromagnet, or in other words, while the armature 64 remains held in attracted position by the electromagnet.

When the temperature to which the thermostat is responsive drops below the temperature for which the device is set, the tripping lever 135 is turned in a clockwise direction (Figure 1) to position to permit the spring arm 48—assuming, of course, that the armature is still in attracted position—to move to the position in which it closes the switch through the pin or switch operating member 93, the arm 48 thereupon maintaining the switch in closed position as long as the thermoelectric generator is heated by the pilot light on other flame.

From the foregoing it will be apparent that the armature 65 is released only upon extinguishment of the pilot light or other flame and that, therefore, a resetting of the device is required only after the valve is closed by extinguishment of the pilot flame. The thermostat or condition responsive control operates through a part of the mechanism through which the valve is maintained open by the armature when the armature is in attracted position and the "on" and "off" operation of the thermostat control is accomplished without releasing the armature, or, in other words, while the armature is held in attracted position by the electromagnet. As a result, the device is fully self-operating or automatic except when it operates to safety position upon extinguishment of the pilot light, which usually occurs infrequently.

The switch or switch contact plate 90 is illustrative of a controlling member. It is to be understood that this controlling member may be in the form of a valve member held in open position by the spring arm 48 and operable to closed position when the spring arm is released by the thermostat control or by the release of the armature upon extinguishment of the pilot light.

It is to be further understood that the arm 48, instead of being in the form of a spring arm, may be in the form of a rigid arm pivoted to the cam lever 42 and held in operating position and returned to that position by a tension spring connected between the arm 48 and another suitable part. In the case of a rigid pivoted arm, suitable abutment means would be provided for limiting the pivotal action of the arm to hold it in its proper position.

The embodiment of the invention shown in the drawings is for illustrative purposes only, and it is to be expressly understood that said drawings and the accompanying specification are not to be construed as a definition of the limits or scope of the invention, reference being had to the appended claims for that purpose.

I claim:

1. In combination, a fluid supply pipe, a controlling member having an operating position for the flow of fluid through said pipe and a safety position shutting off the flow of fluid through said pipe, a reset member mounted for movement to

reset and released positions, an actuator member mounted for movement to resetting and released positions and cooperable with said reset member, when same is in released position, to reset said reset member to reset position by movement of said actuator member from released position to reset position, means for holding said reset member in reset position, an operating arm for actuating said controlling member to operating position by cooperation of said actuator member therewith upon movement of said actuator member from reset position to released position and only when said reset member is held in reset position, means for holding the parts in cooperative relationship, and condition responsive means having mechanical cooperation with said operating arm for releasing, by mechanical actuation of said arm by said condition responsive means, said controlling member for movement to safety position while said reset member is held in reset position.

2. In combination, a fluid supply pipe, a controlling member having an operating position for the flow of fluid through said pipe and a safety position shutting off the flow of fluid through said pipe, a reset member mounted for movement to reset and released positions, an actuator member mounted for movement to resetting and released positions and cooperable with said reset member, when same is in released position, to reset said reset member to reset position by movement of said actuator member from released position to reset position, means for holding said reset member in reset position, an operating arm for actuating said controlling member to operating position by cooperation of said actuator member therewith upon movement of said actuator member from resetting position to released position and only when said reset member is held in reset position, means for holding the parts in cooperative relationship, said operating arm being pivoted on said reset member for swinging movement about its pivot on said reset member to actuate said operating member to operating position and to release said operating member for movement to safety position, and condition responsive means having mechanical cooperation with said operating arm for releasing, by mechanical actuation of said arm by said condition responsive means, said controlling member for movement to safety position while said reset member is held in reset position.

3. In combination, a fluid supply pipe, a controlling member having an operating position for the flow of fluid through said pipe and a safety position shutting off the flow of fluid through said pipe, a reset member mounted for rectilinear movement to reset and released positions, an actuator member mounted for rectilinear movement to resetting and released positions and cooperable with said reset member, when same is in released position, to reset said reset member to reset position by movement of said actuator member from released position to reset position, means for holding said reset member in reset position, an operating arm for actuating said controlling member to operating position by cooperation of said actuator member therewith upon movement of said actuator member from resetting position to released position and only when said reset member is held in reset position, means for holding the parts in cooperative relationship, and condition responsive means having mechanical cooperation with said operating arm for releasing, by mechanical actuation of said

arm by said condition responsive means, said controlling member for movement to safety position while said reset member is held in reset position.

4. In a switch of the class described, in combination, a reset member mounted for movement to reset and released positions, an actuator member mounted for movement to resetting and released positions and cooperable with said reset member, when same is in released position, to reset said reset member to reset position by the movement of said actuator member from released position to reset position, means for holding said reset member in reset position, switch means, a switch operating member actuated to position closing said switch means by cooperation with said actuator member upon movement of said actuator member from resetting position to released position only when said reset member is held in reset position, means for holding the parts in cooperative relationship, and condition responsive means having mechanical cooperation with said operating arm for releasing, by mechanical actuation of said arm by said condition responsive means, said switch means for movement to open position while said reset member is held in reset position.

5. In a switch of the class described, in combination, a reset member mounted for rectilinear movement to reset and released positions, an actuator member mounted for rectilinear movement to resetting and released positions and cooperable with said reset member, when same is in released position, to reset said reset member to reset position by the movement of said actuator member from released position to reset position, means for holding said reset member in reset position, switch means, a switch operating member actuated to position closing said switch means by cooperation with said actuator member upon movement of said actuator member from resetting position to released position only when said reset member is held in reset position, means for holding the parts in cooperative relationship, and condition responsive means having mechanical cooperation with said switch operating member for releasing, by mechanical actuation of said switch operating member by said condition responsive means, said switch means for movement to open position while said reset member is held in reset position.

6. In combination, a fluid supply pipe, a controlling member having an operating position for the flow of fluid through said pipe and a safety position shutting off the flow of fluid through said pipe, a reset member mounted for movement to reset and released positions, an actuator member mounted for movement to resetting and released positions and cooperable with said reset member, when same is in released position, to reset said reset member to reset position by movement of said actuator member from released position to reset position, means for holding said reset member in reset position, a cam lever pivoted on said reset member, cam means on said actuator member for cooperation with said lever, an overtravel spring operating arm carried by said cam lever for actuating said controlling member to operating position by movement of said actuator member from resetting position to released position and only when said reset member is held in reset position, means for holding the parts in cooperative relationship, and condition responsive means having mechanical cooperation with said overtravel spring operating arm for releasing, by

mechanical actuation of said arm by said condition responsive means, said controlling member for movement to safety position while said reset member is held in reset position.

5 7. In combination, a fluid supply pipe, a controlling member having an operating position for the flow of fluid through said pipe and a safety position shutting off the flow of fluid through said pipe, a reset member mounted for movement to reset and released positions, an actuator member mounted for movement to resetting and released positions and cooperable with said reset member, when same is in released position, to reset said reset member to reset position by movement of said actuator member from released position to reset position, means for holding said reset member in reset position, a cam lever pivoted on said reset member, cam means on said actuator member for cooperation with said lever, an overtravel spring operating arm carried by said cam lever for actuating said controlling member to operating position by movement of said actuator member from resetting position to released position and only when said reset member is held in reset position, means for holding the parts in cooperative relationship, an indicator arm on said cam lever for indicating by the position of the cam lever the position of said controlling member, and condition responsive means having mechanical cooperation with said overtravel spring operating arm for releasing, by mechanical actuation of said arm by said condition responsive means, said controlling member for movement to safety position while said reset member is held in reset position.

30 8. In combination, a fluid supply pipe, a controlling member having an operating position for the flow of fluid through said pipe and a safety position shutting off the flow of fluid through said pipe, a reset member mounted for movement to reset and released positions, an actuator member mounted for movement to resetting and released positions and cooperable with said reset member, when same is in released position, to reset said reset member to reset position by movement of said actuator member from released position to reset position, means for holding said reset member in reset position, a cam lever pivoted to said reset member and having a cam slot therein, a cam pin carried by said actuator member and engageable in said cam slot for swinging said cam lever in one direction about its pivot on said reset member upon movement of the actuator member to released position with said reset member held in reset position and swinging said cam lever in a counterdirection upon movement of said reset member to released position, means for holding said parts in cooperative relationship, and condition responsive means having mechanical cooperation with said cam lever for releasing, by mechanical actuation of said lever by said condition responsive means, said controlling member for movement to safety position while said reset member is held in reset position.

45 9. In combination, a fluid supply pipe, a controlling member having an operating position for the flow of fluid through said pipe and a safety position shutting off the flow of fluid through said pipe, a reset member mounted for rectilinear movement to reset and released positions, an actuator member mounted for rectilinear movement to resetting and released positions and cooperable with said reset member, when same is in released position, to reset said reset member to reset position by movement of said actuator member from released position to reset position, means for hold-

ing said reset member in reset position, a cam lever pivoted to said reset member and having a cam slot therein, a cam pin carried by said actuator member and engageable in said cam slot for swinging said cam lever in one direction about its pivot on said reset member upon movement of the actuator member to released position with said reset member held in reset position and swinging said cam lever in a counterdirection upon movement of said reset member to released position, means for holding said parts in cooperative relationship, and condition responsive means having mechanical cooperation with said cam lever for releasing, by mechanical actuation of said cam lever by said condition responsive means, said controlling member for movement to safety position while said reset member is held in reset position.

10. In a switch of the class described, in combination, switch means, a reset member mounted for movement to reset and released positions, an actuator member mounted for movement to resetting and released positions and cooperable with

5 said reset member, when same is in released position, to reset said reset member to reset position by movement of said actuator member from released position to reset position, means for holding said reset member in reset position, an operating arm for actuating said switch means to closed position by cooperation of said actuator member therewith upon movement of said actuator member from resetting position to released position and only when said reset member is held in reset position, said switch means being operable to open position upon movement of said reset member to released position with said actuator member in released position, means for holding the parts in cooperative relationship, and condition responsive means having mechanical cooperation with said operating arm for releasing, by mechanical actuation of said arm by said condition responsive means, said switch means for 15 movement to open position while said reset member is held in reset position.
